TILE CUTTING MACHINE

Louis D. Mariutto, Schenectady, N. Y.

Application August 13, 1938, Serial No. 224,805

2 Claims. (Cl. 125—23)

The invention appertains to new and useful improvements in cutting apparatus and more particularly to a machine for cutting tile.

The principal object of the present invention is to provide a machine which can be readily converted for cutting either asphalt, quarry, rubber or other composition tiles.

Another important object of the invention is to provide a machine of the character stated wherein a uniform pressure can be exerted on the cutter bar during the cutting operation.

Still another important object of the invention is to provide a tile cutting machine wherein the cutting operation can be accomplished by one hand of the operator.

These and various other important objects and advantages of the invention will become apparent to the reader of the following specification.

In the drawings:—

20 Figure 1 represents a side elevational view with a portion broken away.

Figure 2 is a top plan view.

Figure 3 is a transverse sectional view.

25 Figure 4 is a vertical sectional view on the line 4—4 of Figure 1.

Figure 5 is a fragmentary detailed sectional view showing a modified form of cutter.

Figure 6 is a fragmentary detailed sectional view of still another form of cutter.

30 Figure 7 is a perspective view of the adjustable straight edge.

Referring to the drawings wherein like numerals designate like parts, it can be seen that numeral 5 represents the table having the permanent or fixed straight edge 6 along one edge portion thereof. Parallel to the straight edge 6, the table 5 is formed with a slot 7 for receiving the bolt 8 which extends downwardly through the slot 9 of the adjustable straight edge 10 and 40 through the slot 7, below which the same is equipped with a nut 11. One end of the straight edge 10 is cut off as at 12 to form a ninety degree angle.

45 Numeral 13 represents the base plate upon which are the runners 14 for supporting the aforesaid table 5 and as is clearly shown in Figure 1, the cutter bar supporting and tensioning means is represented by a pair of assemblies generally referred to by numeral 15. Each of these assemblies 15 consists of a vertically extending barrel 16 rising from the corresponding end of the base plate 13 and formed with a pair of slots 17 at diametrically opposite sides thereof. These slots extending vertically and have the 55 cutter bar 18 extending therethrough. The cut-

ter bar 18 extends entirely across the machine with its end portions disposed through the assemblies 15 and is provided with a reduced portion 19 at one end and the reduced intermediate portion 20 which portions are cooperative with 5 the levers 21 and 22, respectively, each mounted on the barrel 16 of one of the assemblies 15. These levers 21 and 22 are of substantially bell-crank-shape mounted on pivot pins 23 and it may be desirable that the lever 22 has the handle 24. 10

Each of the barrels 16 is provided with a cap 25 downwardly through which is feedable the adjusting screw 26 having the knurled head 27. The lower end of this screw 27 has the plate-like portion 28 ridable against the spring 29 15 which in turn bears against the ball 30 which is in riding relation with the cutter bar 18, the cutter bar 18 resting on the plate 31 which is supported by the spring 32, the spring 32 being interposed between the intermediate runner 33 20 and the said plate 31.

As is shown in Figure 2, the intermediate portion of the cutter bar 18 is formed with an opening 34 in which is mounted the disk-type cutter 35, a bolt 36 extending through the bar 25 for mounting the cutter and also extending beyond one side portion thereof to connect the link 37 with the bar 18. This link extends to pivotally connect as at 38 to the intermediate portion of the hand lever 39 and this hand lever 30 is, in turn, connected at its lower end as at 40 pivotally to the base frame.

Obviously, by pressing downwardly on the levers 21, 22 the foot portions of these levers can be urged against the bar 18 so as to depress the 35 bar and hold the same against the tension of the spring 32, thus firmly holding the cutter bar downwardly so that the cutting element 35 will be in a position to cut through the tile placed on the table 5. Obviously the cutter bar is moved 40 by the hand lever 39 and when the cutter bar 18 moves to the position where the reduced portion 19 and the reduced portion 20 have approached the levers 21 and 22, the cutter bar 45 will be released so that the cutter element will become removed from the material being cut.

A modified form of cutter is shown in Figure 8 and is especially adapted for cutting rubber tile, the same consisting of the block structure 41 secured as at 42 in the opening 34 of the cutter 50 bar 18.

The block 41 is slotted to receive the plate 43 preferably on an angle of approximately ninety degrees with respect to the cutter bar 18.

It will be observed in Figures 1, 3 and 4 that 55

the table 5 has a slightly convexed top surface. In other words, the top surface is curved transversely and the purpose for this is that when the tile has been cut or scored, downward pressure on the ends, that is, on opposite sides of the scored line will result in the breaking of the tile directly on the platform or table 5.

5 A slightly modified form of cutter or scorer is shown in Figure 9 and this consists of the block 44 having the recess 45 therein for receiving the pointed pin 46 which is held in place by the set screw 47. The block 48 is provided with the head portion 49 for rest upon the cutter bar 18 and a cross pin 50 holds the block in position with respect to the bar 18. This type 10 is especially adapted for scoring quarry tile.

10 While the foregoing specification sets forth the invention in specific terms, it is to be understood that numerous changes in the shape, size and materials may be resorted to without departing from the spirit and scope of the invention 15 as claimed hereinafter.

15 Having described the invention, what is claimed as new is:—

1. A tile cutting machine comprising a table, a cutter bar for travel over the table, means for operating the bar, and tensioning means for the bar, said tensioning means consisting of a pair of assemblies one at each end of the machine, each of the said tensioning assemblies including a spring-pressed ball for riding engagement with the cutter bar, and spring supporting means for the bar underlying said spring-pressed ball.

2. A tile cutting machine comprising a table, a cutter bar for travel over the table, means for operating the bar, and tensioning means for the bar, said tensioning means consisting of a pair of assemblies one at each end of the machine, each of the said tensioning assemblies including a spring-pressed ball for riding engagement with the cutter bar, and retaining means for retaining the cutter bar in work-engaged position, and release means automatically releasing the retaining means at a predetermined extent of travel 20 of the cutter bar.

LOUIS D. MARIUTTO.
